VISOR FOR AUTOMOBILE HEAD LAMPS

David Pattis, Chicago, Ill.

Application March 28, 1955, Serial No. 35,238

Term of patent 3½ years

(Cl. D48—32)

Fig. 1.

Fig. 2.

Fig. 4.

Fig. 3.

Fig. 1 is a perspective view of a visor for automobile head lamps, showing my new design.

Fig. 2 is a top plan view of the same.

Fig. 3 is a front elevational view of the same.

Fig. 4 is a side elevational view of the same.

I claim:

The ornamental design for a visor for automobile head lamps, substantially as shown.
